HAIR SPRAYER OR THE LIKE

Douglas W. Anderson, Palatine, Ill., assignor to Burgess Vibrocrafters, Inc., Grayslake, Ill., a corporation of Delaware

Filed Aug. 29, 1960, Ser. No. 61,920

Term of patent 14 years

(Cl. D62—2)

Fig. 1

Fig. 2

Fig. 6

*Fig. 3Fig. 4Fig. 5*Fig. 1 is a front perspective view of a hair sprayer or the like embodying my new design;

Fig. 2 is a right side elevational view (the left side being a mirror image thereof);

Fig. 3 is a front elevational view;

Fig. 4 is a rear elevational view;

Fig. 5 is a top plan view, and

Fig. 6 is a longitudinal sectional view showing details of the top portion of the hair sprayer or the like.

I claim:

The ornamental design for a hair sprayer, substantially as shown and described.
